(57) **CLAIM**

The ornamental design for a language learning device, as shown and described.

DESCRIPTION

FIG. 1 is a front elevational view of a language learning device of the present invention;

FIG. 2 is a rear elevational view of the language learning device of FIG. 1;

FIG. 3 is a right side elevational view of the language learning device of FIG. 1;

FIG. 4 is a left side elevational view of the language learning device of FIG. 1;

FIG. 5 is a top plan view of the language learning device of FIG. 1; and,

FIG. 6 is a bottom plan view of the language learning device of FIG. 1.
